UNITED STATES PATENT OFFICE.

WILFRID LUMLEY, OF CONNEAUT, OHIO, ASSIGNOR TO GENERAL ELECTRIC COMPANY,
A CORPORATION OF NEW YORK.

LIGHTING-FIXTURE.

1,230,737.

Specification of Letters Patent. Patented June 19, 1917

Application filed May 5, 1913. Serial No. 765,444.

To all whom it may concern:

Be it known that I, WILFRID LUMLEY, a citizen of the United States, residing at Conneaut, in the county of Ashtabula, State of Ohio, have invented certain new and useful Improvements in Lighting-Fixtures, of which the following is a specification.

My invention relates to chandeliers and other lighting fixtures intended to carry 10 electric lights, and more particularly to the electrical connections between the body or junction part employed in such fixtures and the arms. I have hereinafter described my invention as specially adapted and applied 15 in connection with the chandelier shown and described in United States Letters Patent No. 1,045,273 granted November 26, 1912 to Wilbur H. Fisher, this being an application in which the reliability of electrical connection 20 which my invention affords has proved of great practical value. While, however, my invention extends to the specific features and details of the embodiment herein shown and described, which are important on account 25 of their specific advantages, yet the invention is not confined thereto, but can be otherwise carried out and applied, as will be evident both from the following description and from my claims. Various advantages 30 that can be secured in connection with my invention will hereinafter become apparent.

In the construction set forth in the Fisher patent, one of the electrical contacts where- 35 by connection is made between an arm circuit and a body circuit is resilient, and when an arm is inserted in the body this springy contact is first deflected and bent sidewise by coming against the other contact and then 40 springs back so that the other contact rests in a sharp angle in the spring and is in a manner interlocked with it without necessarily having any engagement except at this one place. While the electrical connection 45 thus secured would be entirely satisfactory both theoretically and practically if the arm fitted in the socket without any play, it will upon consideration be seen that the form of contact shown in the Fisher patent does not 50 allow full advantage to be taken of the resilience of the material in maintaining engagement between the arm and the body contacts when there is for any reason con- 55 siderable up and down play of the arm in the socket. This defect is due to the fact

that the springy contact must needs be resiliently deflected to a greater extent during the insertion of the arm in the socket than after the arm has been pushed home to its final position. In accordance with my invention, the interaction of the arm and body contacts can be made such that the utmost play of an arm that is ever likely to occur under any conditions may take place without interruption or impairment of the electrical connection, and full advantage can be taken of the resilience of springy or resilient contacts in maintaining the connection. These results can be secured by making the parts so that when the arm is inserted in the socket the resilient contact will be bent or sprung to one side without springing back to any considerable extent, or so that the resilient contact will be engaged at more than one place and forced against one 75 of the surfaces so engaging it by the other.

In the accompanying drawings, Figure 1 is a perspective view of the end of a chandelier arm adapted for the fixture shown in the Fisher patent above mentioned and having contact members constructed in accordance with my invention.

Fig. 2 is a side elevation of the end portion of such an arm showing somewhat more clearly than Fig. 1 the exact form of the 85 contacts when the arm is not in the body.

Fig. 3 is a fragmentary vertical section showing an arm with contacts like those shown in Figs. 1 and 2 in place in one of the arm-holes of the body shown in the Fisher 90 patent above mentioned, this figure showing the relation of the arm contacts to the parts of the body and the form which they assume when the arm is in place in the body.

In the particular device herein illustrated 95 and described, the arm contacts *a* are the resilient ones, as in the Fisher patent, and the engagement and securing of the arm *A* in the body *B* and its construction and internal features are the same as in the Fisher patent, and the body contact means *i* and the construction of the body *B* are also exactly as shown in the Fisher patent, the body *B* having an external shell *S* and a central portion *I* of insulating material in which 100 are sockets *i* for the arms which afford bearing for projections *a'*, *a''* on the arms so as to prevent them from turning, and this "inner body" *I* also having chambers *i'* which are in effect prolongations or exten- 110

sions of the sockets i in which the body contacts i^5 are exposed and engage with the arm contacts a ,—yet, although when an arm is in place the body contacts i^5 lie between the arm contacts a , as in the Fisher patent, the arm contacts a and their interaction with the body contacts i^5 and the associated parts are nevertheless quite different from what is shown in the Fisher patent, both the modes of action above described being present.

As shown in the drawings, when the arm A is not in the body B its contact members a project from the end of the arm in approximate parallelism—or, to be more accurate, for a short distance with very slight divergence and for a greater additional distance with slight convergence—for distance somewhat greater than the distance of the body contacts i^5 from the end of the arm when the arm has been pushed home in the socket, the distance apart of the approximately parallel portions a^{11} being as shown everywhere less than the distance apart of the outer surfaces of the contacts i^5 , and are then bent or flared outward at a^{12} . The diverging portions a^{13} of the contacts beyond the bends a^{12} are of such length that the distance between their outer free ends a^{14} is substantially less than the internal diameter of the barrel sockets i , and the ends a^{14} are preferably rounded (as shown, by curling them quite sharply inward) so that when an arm is inserted in the body or withdrawn they will slide easily against surfaces with which they come in contact.

When, therefore, the arm A is inserted in the socket i and pushed home, the body contacts i^5 encounter the diverging portions a^{13} of the arm contacts a and force them apart, and also bend the portions a^{11} apart and eventually come between them. In the early part of this movement of the arm contacts a inward over the body contacts i^5 , the only portions of them that suffer deformation are those between the end of the arm and the points of engagement with the body contacts, the deformation being merely a resilient bending apart of these portions which tends to make them concave outward. With the relative proportions and arrangement of the part shown, however, the free ends a^{14} of the contacts a will come against the upper and lower walls of the chambers i^4 and so be prevented from spreading any farther apart before the inward movement of the contacts a is completed, so that the necessary separation of the portions of the contacts a which traverse the contacts i^5 after this will involve both a bending apart adjacent the end of the arm such as above described and also some bowing or bending inward against the contacts i^5 of portions of the contacts a between the ends of the arms and the free ends a^{14} such as would make these portions concave inward. In the final position of the

arm in the body, therefore, each spring contact a projects from the inner end of the arm A past the body contact means i^5 and is resiliently flexed between its points of lateral engagement at its free end a^{14} and at the intermediate point in its length where it lies against the body contact i^5 , this flexure being the reverse of its flexure adjacent its fixed end that results merely from the presence of the contact i^5 and serving to augment its resilient pressure against this contact i^5 . This double lateral flexure will permit a very considerable up and down play or tilting of the arm in its socket with nothing more than a decrease in the deformation of one arm contact a and its resilient pressure upon the corresponding body contact i^5 and the opposite effect upon the other, without the slightest possibility that either arm contact a should even for an instant be out of engagement with its body contact i^5 .

While any suitable material may be employed, for the sake of combining the utmost resilience with good electrical conductivity it is preferable to make the arm contacts a of cold rolled sheet copper.

What I claim as new and desire to secure by Letters Patent of the United States, is:—

1. In an electric connection the combination of a socket and a removable arm adapted to enter said socket, said socket having therein a stationary contact and said arm having a resilient contact extending therefrom and engaging said stationary contact at an intermediate point in said resilient contact and having its free end engaging the wall of said socket whereby the resilient contact is flexed by said wall and thereby pressed firmly against said stationary contact under any tilting movement of said arm.

2. In an electric connection the combination of a socket and a removable arm having a portion adapted to enter said socket, said socket having a stationary contact therein and said arm having extending therefrom a resilient contact adapted to be engaged at an intermediate point by said stationary contact and thereby flexed in one direction and adapted to be engaged at its free end by the wall of the socket and thereby flexed in the opposite direction.

3. The combination with a lighting fixture body or junction part having a socket with electrical contact means exposed therein, of a removable arm in said socket having a pair of spring contacts projecting from its end at opposite sides of said body contact means into engagement therewith and resiliently bent apart thereby, the portions of said spring contacts beyond said body contact means extending into engagement with the walls of the socket and being thereby resiliently flexed toward one another.

4. The combination with a lighting fixture

body or junction part, having a socket with electrical contact means exposed therein, of a removable arm in said socket having a spring contact projecting from its end and engaging said contact means and thereby bent in one direction, the portion of said spring contact extending beyond said contact means extending into engagement with the wall of the socket and being thereby resili-

ently flexed in a direction opposite to that caused by engagement with the contact means.

In witness whereof, I have hereunto set my hand this 26th day of April, 1913.

WILFRID LUMLEY.
